UNITED STATES PATENT OFFICE.

HERBERT E. VAN DORN, OF CHICAGO, ILLINOIS.

CAR COUPLER.

Application filed August 5, 1921. Serial No. 489,952.

To all whom it may concern:

Be it known that I, HERBERT E. VAN DORN, a citizen of the United States, residing at Chicago, county of Cook, State of Illinois, 5 have invented a certain new and useful Improvement in Car Couplers, and declare the following to be a full, clear, and exact description of the same, such as will enable others skilled in the art to which it pertains to make and use the same, reference being had to the accompanying drawings, which form a part of this specification.

In some types of automatic car couplers as, for example, that disclosed in my prior 15 application Serial No. 317,111, filed August 13, 1919, there is nothing exposed to show a switchman or the like in just what position the locking block is and he must therefore guess at it. The principal object of the 20 present invention is to provide an automatic car coupler with an indicator visible from the exterior of the coupler, to show exactly the position in which the locking block or dog may be at any given instant. This may 25 conveniently be accomplished by rigidly fastening the usual handle, employed for manual operation, directly to the locking dog or to actuating parts which are compelled to move in unison with the dog; thus combining in one device the functions of a handle and of an indicator.

In applying my combined handle and indicator to the coupler disclosed in my aforesaid application, certain changes in the controlling means for the lock, which is in the 35 form of a bail, are desirable and, viewed in one of its aspects, my invention may be said to have for its object to simplify and improve the controlling means for a horizontally-swinging locking bail.

The various features of novelty whereby my invention is characterized will hereinafter be pointed out with particularity in the claims; but, for a full understanding of my 45 invention and of its objects and advantages, reference may be had to the following detailed description taken in connection with the accompanying drawings, wherein:

Figure 1 is a horizontal section through 50 a coupler arranged in accordance with a preferred form of my invention, a fragment of

a co-operating coupler being shown in dotted lines;

Fig. 2 is a view similar to Fig. 1, only a fragment of the coupler being shown, and 55 the parts being in unlocked positions;

Fig. 3 is a section taken approximately on line 3—3 of Fig. 1; and

Fig. 4 is a perspective view of one of the eccentric sleeves forming the pivotal supports for the locking dog or bail. 60

Referring to the drawings, 1 represents a hollow coupler head having at one side a forwardly-projecting hook, 2, adapted to enter a chamber, 3, in the front end of the 65 head beside the hook on a co-operating coupler. Within the chamber 3 at the base of the hook is a vertical pin, 4, on which swings a locking bail, 5. The locking bail does not bear directly upon the pin 4 but is separated therefrom by means of eccentric sleeves, 6, one in the upper arm of the bail and the other in the lower arm. The upper eccentric sleeve has a horizontal flange or wing, 7, projecting radially from the lower 70 end while the lower sleeve has a similar flange or wing, 7, projecting radially from the upper end thereof. The two flanges or wings, 7, are provided with peripheral notches, 8, which, when the parts are assembled, lie directly above each other. Surrounding and journaled on the pin 4 between the top of the bottom eccentric sleeve and the bottom of the upper eccentric sleeve, 85

is an actuating plate, 9, having arms, 10 and 11, extending respectively upwardly into and through the notch 8 associated with the upper eccentric sleeve and downwardly through the notch associated with the lower eccentric sleeve. The inner ends of the arms 90 of the locking bail are provided with notches, 12, registering with the notches 8 but somewhat longer than the latter when measured angularly about the axis of the pin 4. The arms 10 and 11 project into 95 these notches, 12, so that when the actuating plate is turned in one direction or the other, the first effect is to turn the eccentric sleeves and shift the locking bail bodily in the direction of its length, and then swing 100 the bail about its pivotal axis. A spring, 13, arranged between a projection, 14, on

one end of the actuating plate, and rearwardly-directed shoulders, 15, within the hollow hook of the coupler, tends constantly to swing and hold the actuating plate in its locking position.

The parts heretofore described are all, except perhaps as to minor details, the same as the corresponding parts in the coupler shown in my aforesaid application and

10 therefore need not be further explained. The actuating plate, 9, has two rearwardly-projecting ears, 16, between which lies one end of a connecting rod, 17; a pin, 18, passing through the ears and the connecting rod 15 to secure them pivotally together. The opposite end of the connecting rod is pivotally connected, as by means of a pin, 19, to an arm, 20, fixed to and extending radially from a vertical uncoupling shaft, 21. The 20 shaft, 21, has fixed thereto at one end, on the exterior of the coupler, an actuating lever or handle, 22. Whenever the handle or lever 22 is actuated, the locking dog or bail, 5, is also actuated. Similarly, whenever the locking 25 dog or bail moves the actuating lever or handle is also caused to move. In other words, the actuating lever or handle on the exterior of the coupler always shows accurately the position in which the locking dog or bail is 30 at any given time.

The spring, 13, tends always to hold the locking dog or bail in its locking position and therefore it is necessary to provide 35 means which will hold the locking dog or bail in its unlocked position, which means can be tripped, as conditions require. In the arrangement shown there is mounted in the coupler head behind the locking dog a horizontally-swinging pawl, 23, provided with 40 a spring, 24, tending constantly to swing the nose of the pawl rearwardly; the parts being so proportioned that when the actuating lever or handle is swung into the unlocking position as shown in Fig. 2, the pawl, 23, 45 automatically drops into place behind the rocker arm, 20, preventing the return of the parts to the locking positions until the pawl is tripped. The pawl is provided with a projection, 25, which extends outwardly 50 through an opening, 26, in the wall of the coupler when in the position shown in Fig. 2, and the pawl may readily be tripped by a workman pressing his foot against the projection 25 or by pressing this projection inwardly in any other suitable manner. The 55 pawl may be automatically tripped by the engagement of a co-operating coupler hook with a forwardly-projecting extension, 27, which, with the pawl proper, forms an approximately U-shaped device the arms of which lie respectively in front of and behind the locking bail. When the parts are locked 60 in the open or release positions as indicated in Fig. 2, and two couplers are brought to-

gether, the hook on the one coupler will engage with the inner side of the front end of the pawl member, 27, in the other coupler, swinging this member outwardly away from the longitudinal axis of the coupler head, and at the same time swinging the corresponding pawl forwardly out of engagement with the rocker arm, 20.

I claim:

1. A coupler comprising a chambered head, a locking dog within said head, a spring tending to hold said dog in locking position, an actuating shaft mounted in said head, mechanism between said shaft and said dog for causing said dog to move when said shaft is turned, a spring-actuated pawl in the chamber in the head in position to engage said mechanism and hold the dog in release position after it has been moved into that position, and a part on said pawl projecting to the exterior of said head on one side of the latter to permit the pawl to be manually tripped.

2. A coupler comprising a chambered head, a locking dog within said head, a spring tending to hold said dog in locking position, an actuating shaft mounted in said head, mechanism between said shaft and said dog for causing said dog to move when said shaft is turned, a spring-actuated pawl in the chamber in the head in position to engage said mechanism and hold the dog in release position after it has been moved into that position, said pawl being arranged behind said locking dog, and an extension projecting from the base of said pawl forwardly and in advance of said dog, said extension being shaped to engage with a part on a co-operating coupler to trip the pawl when two couplers come together, said pawl also having a part extending to the exterior of the coupler on one side thereof to permit the pawl to be manually tripped.

3. A car coupler provided with a horizontally swinging locking dog, a vertical actuating shaft, an arm fixed to and projecting radially from said shaft, a connecting rod between said arm and said dog, and an actuating handle fixed to the shaft on the exterior of the coupler so as to serve as a combined handle and an indicator of the position of the locking dog.

4. A coupler comprising a chambered head, a horizontally swinging locking dog within said head, a spring tending to hold said dog in locking position, a vertical actuating shaft mounted in said head and provided with an arm projecting radially therefrom, a connecting rod between said arm and said dog, and a spring-actuated pawl in the chamber in the head in position to engage said arm to hold the dog in its released position.

5. A coupler comprising a chambered

head, a locking dog within said head, a spring tending to hold said dog in locking position, actuating means for moving said dog into a released position, a spring-actuated pawl in the chamber in the head in position to engage said mechanism and hold the dog in released position after it has been

moved into that position, said head having an opening in one side thereof, and a part on said dog projecting through said opening. 10

In testimony whereof, I sign this specification.

HERBERT E. VAN DORN.
